MOTION PICTURE CAMERA

Shigeo Mizukawa, Ohmiya, and Masahiro Fukuda, Tokyo,
Japan, assignors to Fuji Shashin Film Kabushiki Kaisha,
Minamiashigara-machi, Ashigarakami-gun, Japan

Filed Apr. 2, 1970, Ser. No. 22,201

Term of patent 14 years

Int. Cl. D16—01

U.S. Cl. D61—1

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of a motion picture camera showing our new design;

FIG. 2 is a rear elevational view thereof;

FIG. 3 is a left side elevational view of FIG. 1;

FIG. 4 is a bottom plain view thereof;

FIG. 5 is a perspective view of another embodiment of FIG. 1 camera wherein the various switches and the camera face plate have been rearranged;

FIG. 6 is a rear elevational view of the FIG. 5 embodiment;

FIG. 7 is a left side elevational view thereof;

FIG. 8 is a bottom plan view thereof;

FIG. 9 is a perspective view of yet another embodiment of the FIG. 1 camera, wherein several switches have been changed and openings re-arranged while the face plate remains uniform in color with the main body portion;

FIG. 10 is a rear elevational view of the FIG. 9 embodiment;

FIG. 11 is a left side elevational view thereof; and

FIG. 12 is a bottom plan view thereof.

We claim:

The ornamental design for a motion picture camera, as shown and described.
